TYPEWRITING MACHINE

Ronald D. Dodge, Rochester, N. Y., assignor to
 International Business Machines Corporation,
 New York, N. Y., a corporation of New York

Application April 8, 1937, Serial No. 135,639

33 Claims. (Cl. 197—84)

This invention relates to typewriting machines. An object of the invention is to provide an improved carriage feed mechanism.

An object is to provide feed mechanism which causes the carriage to be advanced a variable amount depending upon the widths of the characters typed.

An object is to provide a carriage feed mechanism in which the extent of the feed imparted to the carriage as an incident to each character printed is based not only upon the width of the character printed but also upon the width of the character previously printed.

Another object is to provide carriage feed mechanism which has presetable means for controlling the feeding of the carriage for the next character printed.

Another object is to provide novel means actuated by power for causing the carriage to be fed variable extents.

There has grown in recent years a practice of printing advertising matter, booklets, catalogues and other matter by means of plates which are prepared from typewritten copy by some suitable process of photo-engraving such as the photo off-set process. In this process, typewritten copy is prepared and is subsequently photographed and transferred to a suitable printing plate or transfer medium such as a lithographic stone. The type characters used in typewriting machines are a compromise due to the fact that typewriter feed mechanisms cause the carriage to feed equal amounts for each character printed which requires that many of the characters, particularly those of great width must be compressed in width in order to avoid excessive spacing of the narrower letters. This spoils the effect of certain characters and makes them less legible than the others because of the fact that they are usually compressed more than is desirable to ensure a good type face. Thus, the letters M and W, for instance, which in ordinary printing are quite wide in relation to other letters, are so compressed as to lose some of their legibility and good appearance as compared with the same characters in well designed fonts of type used in printing from printer's type.

In order that the typewritten copy used in preparing plates by any of the processes commonly practiced at present may have the good appearance and legibility of printed matter prepared from well designed printer's type, it is desirable that the type characters printed by the typewriter have the same proportions and be of the same style as those used in ordinary printers

fonts of type or the type slugs cast by the matrices used in type founding machines such as the linotype and intertype. However, if standard printer's type faces are used in typewriting machines, some of the letters like the letter I, for instance, are much narrower and others, like the letters M and W, are much wider than the space ordinarily allotted to each character in designing the spacing mechanisms of typewriting machines. Thus, if an ordinary typewriter is equipped with types having faces of standard design, the letter I and other narrow characters will receive an excessive spacing since the spacing allotted to each character must be large enough to accommodate the widest character printed. In order to get the same visual effect with typewritten matter as with type-set matter, it is desirable that the feeding of the typewriter carriage be varied in accordance with the width of the letter both for reasons of compactness and to improve the appearance of the copy.

The present invention aims to provide spacing mechanism suitable for use in typewriting machines which permits the use of standard type faces by varying the extent of feed of the carriage according to the widths of the characters printed whereby they may be set as close together as possible and yet be as legible as type set matter printed from well designed type.

This introduces a somewhat difficult problem owing to the fact that it is standard practice to mount the types on the type bars so that the characters on the type bars will be centered with respect to the type guide. It is desirable, therefore, in order to avoid introducing new techniques in aligning the types and to avoid the use of special types as far as possible, that the spacing mechanism operate for each character typed in accordance with both the width of that character and the width of the letter previously typed.

Another object of the invention is to provide means for controlling the spacing of each character in accordance with the amount of spacing of the character immediately preceding.

Various other objects, advantages, features of the present invention will be particularly pointed out in the following description and claims and will be apparent from a study of the descriptive claims and the accompanying drawings.

In the drawings:

Fig. 1 is a vertical section through the machine;

Fig. 2 is a plan view of the carriage feed mechanism and portions of the keyboard;

Fig. 3 is an enlarged rear elevation of the carriage feed mechanism;

5 Fig. 3A is a section on the line 3A—3A in Fig. 3;

Fig. 4 is a vertical section on the line 4—4 in Fig. 3;

Fig. 5 is a detail view of one of a single lobe cam.

10 The present invention, purely for convenience in description, has been illustrated in the drawings as applied to the well known International electric writing machine formerly known as Electromatic. However, it is not limited in its 15 application to the specific form of power operated typewriter, but may be applied particularly to other typewriters as well, regardless of whether they are power operated or manually operated. It is not desired to be limited, therefore, to the specific type of machine selected for 20 purposes of illustration. The typewriting machine has been changed in relatively few particulars since the object of the present invention is primarily to provide variable spacing mechanism and in all respects except the construction 25 of the spacing mechanism and certain changes in the keyboard, the machine may be identical with the standard commercial machine, now well known in the art. Since the machine is well 30 known in the art only a brief general description of its construction will be given herein.

The carriage is generally designated 1 in Fig. 1 and supports the usual platen 2 mounted by means of antifriction rollers on the rails 3 which 35 are supported by the main frame of the machine. The type basket is generally designated 4 and has the usual type bars 5 pivoted in the segment 6. Associated with each type bar is a toggle 7, one member of which is connected by a link 8 to a 40 sub-lever 9 pivoted on rod 10. Each sub-lever 9 is connected by a link 11 to a cam unit 12 which cooperates with a power roller 13. The power roller 13 rotates constantly in the direction of the arrow (Fig. 1).

45 Normally double lobe cam units are used to operate the type bars of International electric writing machine but, for reasons which will be explained hereinafter, the type bars in the present case are operated by single lobe cams similar to the one shown in Fig. 5. The cam unit 12 has a dwell 14a of approximately 180° followed by a rise 14b. Each cam unit associated with a type bar is controlled by a key lever 15 pivoted on a rod 10 which also serves for a pivot for the 50 sub-levers 9. Whenever one of the key levers 15 is depressed, the cam 14 is caused to rotate slightly until it engages the power roller 13 which thereafter turns the cam in the proper direction. During the first half revolution of 55 the cam 14 by the power roller 13 the cam unit remains dormant, however, when the rise 14b cooperates with the power roller, the cam unit is rocked to draw down the proper link 11 and cause the type bar to be operated in the well 60 known manner. So far as the operation of the single lobe cam unit is concerned this is well known and described in the Patent No. 1,753,450.

Normally, the movement of the type bar to 70 printing position operates escapement mechanism which causes the carriage 1 to be spaced one unit for each impression, this spacing operation of the carriage taking place after the impression has been made and is effected in consequence of the type bar striking a universal bar. 75 In the present machine, the spacing is effected

before the type bar commences to move to the printing position and is varied according to the character printed by the type bar selected. Pivotally mounted underneath all the key levers 15 are three bails designated 18, 19, and 20 (Figs. 1 and 2). Secured to each key 15 is a plate 15a having a downwardly extending lug 15b cooperating with one of the bails 18, 19, and 20 whereby when a key is operated, it will cause one of the bails 18, 19, or 20 to become depressed.

10 The three bails cause different increments of spacing, the bail 18 controlling the greatest amount of spacing while the bail 20 controls the least amount of spacing, the bail 19 being intermediate. In other words, when bail 20 is depressed the carriage feed mechanism is caused to feed the carriage the smallest space, while when bail 18 is depressed, the carriage is fed the greatest space. The plates 15a are so mounted on the keys for narrow letters like i, for instance, and the numeral "1" operate bail 20 whereby these characters are spaced a relatively smaller amount than the wider letters like m and w, for instance, the keys for which operate bail 18, these representing the extremes of spacing. The bulk of 20 the keys 15 operate the bail 19 which controls the spacing mechanism for the spacing of letters like A and S.

25 Near the left hand side of the machine, the bails 18, 19, and 20 (see Fig. 2) have link connections with levers 21, 22, and 23, respectively, 30 which are pivotally mounted on the rod 10 and are similar in shape to the key levers 15 but do not have key caps. These levers 21, 22, and 23 control double lobe cam units 12a similar to those 35 normally used to operate the type bars of the International electric writing machine. Each of these cam units 12a has a link connection 24 with one of three bails 25, 26, and 27 pivotally mounted on rod 10 and provided with rubber buffers 28 cooperating with the underside of the frame member 29 supporting the rod 10.

40 The bails 25, 26, and 27 are connected by links 30 with three bell cranks 31, 32, and 33 pivoted at 45 34 in slots formed in a block 35. Each of the bell cranks 31, 32, 33 has an arm provided with upwardly extending lugs designated 31a, 32a, and 33a, respectively, in Fig. 2 and is provided with a restoring spring 36 anchored to a pin carried by the framework. Also loosely pivoted upon the stud 34 carried by block 35 is an arm 37 which is engaged by all the lugs 31a, 32a, and 33a whereby the arm 37 is rocked clockwise whenever any of the bell cranks 31, 32, 33 is rocked clockwise. A third bell crank 38 is pivoted on the stud 34 and has a link connection 39 with a bell crank 40 pivoted upon the rod 10 and provided with a rubber cushion 28. This bell crank 40 is operated by a double lobe cam unit like 12a which is controlled by the lever 41 associated with the space bar 42.

45 Pivoted upon the stud 34 (Fig. 3) are two arms 43 and 44 which are connected by links 45 and 46 to two cams 47 and 48. The cams 47 and 48 are pivoted on a stud 49 carried by 50 a frame 50 which supports the spacing mechanism. The cams 47 and 48 engage rollers 51 located on opposite sides of a link 52 which has a slot embracing the stud 49. A spring 53 anchored to the link 52 and to the framework normally holds the rollers 51 in contact with the dwells of the cams 47 and 48. The link 52 is pivoted at its upper end to an arm 54 which in turn is rotatably mounted on a shaft 55. The arm 54 is connected by a link 56 with a lever 57 which 55

is rotatably mounted on shaft 55. The bell crank 38 is connected by a link 58 with a two-armed lever 59 also rotatably mounted on shaft 55. The shaft 55 as shown in Figs. 2 and 4 is mounted upon anti-friction bearings 60 and 61 carried by the frame 50.

Secured to the shaft 55 (Figs. 1, 2, and 4) is a spiral pinion 62 which meshes with a rack 63 secured to the underside of the carriage 1. 0 Mounted on the rear end of shaft 55 is a ratchet wheel 64 having relatively fine teeth and keyed to the shaft 55 by means of a pin 65 which engages diametrically opposite slots formed in the hub of the ratchet. The arm 54, bell crank 59 and lever 57 are separated by ball thrust bearings comprising disks 67 having holes loosely retaining the balls 68, a plain disk 69 holding these parts in place on a shoulder 55a formed in the rear end of shaft 55, the rear end of shaft 55 being threaded and provided with nuts 55b holding disk 69 on shaft 55.

The bell crank 59 has pivotally mounted thereon a pawl 70 (Fig. 3) actuated into engagement with the ratchet 64 by means of a spring 71. 5 When the space bar 42 is depressed its cam unit 12a is caused to operate, drawing link 39 to the right in Fig. 2 to rock bell crank 38 counterclockwise. This causes link 58 to be pulled downwardly to the right in Fig. 3 thereby rocking bell 10 crank 59 in a clockwise direction. This causes ratchet 64 to be rotated a predetermined extent limited by means of a stop screw 72 carried by a lug formed in the frame 50.

Before proceeding further with the description 5 it is desired to explain how the increments of spacing are distributed on a unit basis. In order to allow for the appropriate spacing of the printed characters, provision has been made for a maximum at six increments of spacing each of 10 the order of .025". The narrow characters like I, the numeral 1, most punctuation marks, are spaced two units. The letters of medium width, like A, S, and N, are assigned four units of spacing, while the widest letters like M and W are 15 assigned six units of spacing. However, this will be explained more fully hereinafter.

Each letter receives not only half the number 20 of units of spacing assigned to it, but also receives an additional spacing which is equal to half of the width of the letter previously typed. The teeth on the ratchet 64 are so spaced that moving the ratchet one tooth space causes the carriage to be moved one unit of spacing or .025". The stop 72 and the linkage operating the bell 25 crank 59 are so designed that the ratchet wheel 64 is rotated two tooth spaces whereby the carriage is fed four units of spacing each time the space bar 42 is operated, this spacing being adopted for words. The spacing of the carriage 30 for the letters is effected by means of the lever 57 and the movements of this lever are controlled both by the cams 47 and 48 and by additional mechanism hereinafter to be described which is pre-set according to the width of each 35 letter type to govern the spacing of the next letter.

Pivottally mounted on the upper end of lever 40 75 is a pawl 73 (Fig. 3) which is actuated into engagement with the ratchet 64 by means of a spring 74. Whenever a character key is depressed, the appropriate bail 18, 19, or 20 is depressed thereby drawing down one of the levers 21, 22, 23 and causing one of the double lobe cams 12a to operate the corresponding bail 25, 26, 27 in a clockwise direction through the me-

dium of links 24. This causes one of the links 30 to be drawn to the right in Figs. 1 and 2 thereby rocking one of the levers 31, 32, 33 in a counterclockwise direction (Fig. 2). By the cooperation of the lugs 31a, 32a, 33a with lever 37, 5 the latter is also rocked counterclockwise, drawing the link 56 to the right (Fig. 3). This causes the lever 57 to rock in a clockwise direction thereby rotating the ratchet wheel 64 by means of pawl 73. The extent to which the ratchet 64 is 10 rotated is dependent upon the position of the cams 47, 48, these cams being normally in the position shown in Fig. 3.

The ratchet 64 will be permitted to rotate six 15 spaces with the parts in the position of Fig. 3 owing to the cooperation of the end of pawl 73 with a pin 75 carried by the arm 54. When the cam 48 is rotated in a clockwise direction, the link 52 is caused to move upwardly and to the left whereby the pin 75 is moved toward the pawl 20 73. Thus, if levers 37 and 32 are operated together, the ratchet wheel 64 will only be rotated five tooth spaces. On the other hand, if arm 37 and bell crank 33 are operated together, the cam 47 will be rotated in a clockwise direction 25 and move the link upwardly to an extent to confine the rotation of ratchet 64 to four units of spacing. The foregoing explanation is based on the assumption that lever 57 always starts from the position of Fig. 3. 30

The lugs 31a, 32a and 33a are suitably cut away whereby bell crank 31 operates only the arm 37; bell crank 32 operates the arm 43 and arm 37, while the bell crank 33 operates both the arm 37 and arm 44. In other words, arm 35 37 is invariably operated by bell cranks 31, 32, 33 whereas arms 43 and 44 are operated only when characters requiring the medium and the smallest spacings are to be printed, lever 37 operating alone only when the widest letters are 40 to be printed. The lever 57 is returned to the position of Fig. 3 by means of a spring 76 anchored to a pin carried by the frame 50 and to a stud 77 in lever 57. The return movement of lever 57 is governed by the extent of movement 45 imparted to the ratchet 64 under control of cams 47, 48.

Pivottally mounted on a stud 78 is a lever 79 having a bent over lug 79a engaging a stop screw 80 carried by a lug formed in the frame 50. A 50 spring 81 is anchored to the arm 79 and to a pin carried by frame 50 tending to rock the lever clockwise into engagement with the stop screw 80. The lever 57 has an arm 57a carrying a roller 82 adapted to engage a lug 79b formed in the 55 lever 79. Pivottally mounted on the upper end of lever 79 is a lever 83 provided with three notches 83a, 83b, 83c on different levels. A pawl 84 is pivottally mounted on the upper end of lever 57 and has a bent over lug 84a adapted to 60 engage notches 83a, 83b, 83c. A spring 85 tends to rock the pawl 84 in a clockwise direction limited by the stud 77.

The left hand end of the lever 83 is guided by means of a strap 86 secured to the rear face of an 65 elongated boss formed in the frame 50. The strap 86 is spaced from said boss by means of collars 87 whereby the lever 83 has a limited amount of rocking movement upon lever 79. A spring 88, connected to the left hand end of lever 83 70 and to a pin carried by frame 50, tends to rock the lever 83 in a counter-clockwise direction. The lever 83 is also provided with two notches 83d and 83e with which cooperates a latch pawl 89 pivoted on a stud 90. A spring 91 attached 75

to the pawl and to a pin carried by a frame 50 normally urges the pawl 89 in a clockwise direction, this movement being limited by a stop screw 92 carried by a lug formed in the casting 50.

5 The extent of which the lever 57 is restored by the spring 76 is dependent upon the position of the levers 79, 83. With the lug 84a a pawl 84 located in the notch 83a of member 83, the spring 76 can retract the lever 57 to the fullest extent 10 equivalent to six units of spacing of the carriage, assuming neither of cams 47, 48 were operated. With lug 84a in the notch 83b, the restoring movement is equivalent to five units of spacing, while the notch 83c is so located as to limit the 15 restoring of lever 57 to four units of spacing.

Each time the bell cranks 31, 32, 33 are operated to rock the lever 57 in a clockwise direction (Fig. 3), the roller 82 on the arm 57a of lever 57 engages the lug 79b and may rock said lever an 20 amount dependent upon the amount of clockwise rotation imparted to the lever 57. For instance, if the letter M is typed, bell crank 31 alone is operated and lever 57 moves in a clockwise direction from the position of Fig. 3 an amount 25 equivalent to six units of spacing. This causes lever 57 to rock lever 79 in a counterclockwise direction moving lever 83 to the left far enough to cause pawl 89 to enter notch 83e. On the other hand, when lever 57 is rotated in a clockwise direction as a consequence of the depression of one 30 of the keys associated with the letters of intermediate width, like A or S, lever 79 is rocked far enough in a counterclockwise direction to cause the pawl 89 to cooperate with notch 83d to hold 35 lever 83 in an intermediate position. Lever 57 is not moved far enough to affect lever 79 when the narrowest characters are typed, roller 82 merely barely touching the lug 79b. This causes levers 79, 83 to remain in the position of Fig. 3 40 when the narrowest characters are typed.

The spring 88 has a tendency to rock the member 83 in a counterclockwise direction, but is inferior in tension to the spring 76 whereby the member 83 is drawn downwardly when the pawl 45 84 moves away from any of the notches 83a, 83b, 83c thereby permitting the member 83 to be held momentarily by the engagement of pawl 89 with one or the other of notches 83d, 83e. This positions the member 83 so that on the return movement of the lever 57 pawl 84 may enter one of the 50 three notches 83a, 83b, 83c and thereafter in the tension of spring 76 will rock member 83 in a clockwise direction disengaging said member from the pawl 89. This permits spring 81 to 55 restore lever 79 to the position of Fig. 3.

Each time the lever 57 is rocked in a clockwise direction the spring 85 rotates the pawl 84 clockwise so as to move the lug 84a to a point in an arc having shaft 55 for a center and of radius 60 equal to the radial distance between the center of shaft 55 and the bottom of notch 83c. This position of lug 84a is determined by stud 77. In other words, with the parts as in the initial position shown in Fig. 3, lug 84a will enter notch 83c during the last portion of the restoring movement of lever 57. With lever 83 displaced to the left only far enough to cause pawl 89 to engage notch 83d, lug 84a will enter notch 83b, while lug 84a will enter notch 83c when lever 83 remains in the position of Fig. 3. Thus, while the levers 79 and 83 will always be restored to the position of Fig. 3, the lever 57 will be restored to any one of three positions determined by the different levels of the notches 83a, 83b, 83c.

75 Summing up the foregoing description, the

member 83 is set differentially each time the spacing mechanism is operated in accordance with the width of the character printed whereby the spacing of subsequently printed characters is dependent not only upon their own width but also upon the width of the previous characters typed. Let it be assumed, for example, that the parts initially have the position shown in Fig. 3, which is the position taken by the parts after a wide letter like M has been typed, calling for the maximum spacing with respect to that character, and that it is now desired to type the letter I calling for the minimum spacing so far as that letter is concerned. When the I key is depressed, the cam unit 12a associated therewith operates the bell crank 33 and also the arm 37 simultaneously. This causes the cam 47 to move to a position to limit the clockwise movement of lever 57 to the minimum amount so far as control by the cams 47, 48 is concerned. Since lever 57 is as far as it can go in a counterclockwise direction, it will be moved in a clockwise direction three units as a consequence of its initial position and one additional unit as a consequence of the control exercised by cam 47. Thus, four units of spacing will be imparted to the carriage. This corresponds to .100". In other words, the carriage is moved three units which is half the width of the letter M plus one unit or half the width of the letter I.

If the A key, for example, had been operated, the cam 48 would have been operated and would cause the lever 57 to move one unit further giving five units of spacing to the carriage. If the letter W were typed, neither of the cams 47, 48 would be operated and the lever 57 would be moved the maximum possible amount causing six units of spacing to be imparted to the carriage.

After each of the above key operations, the lever 79 and member 83 are moved to position the lug 84a in different ones of the notches 83a, 83b, 83c. In the case of the I key, member 83 will not be moved whereby, when the pawl 84 returns as a consequence of the restoration of lever 57, it will enter the notch 83c thereby limiting the return movement of lever 57 to the minimum extent. In the case of the A key, the roller 82 will move lever 79 and member 83 to the intermediate position with pawl 89 cooperating with the notch 83d whereby, on the return movement of pawl 84, it will enter the notch 83b before disengaging lever 83 from pawl 89. In a similar fashion, the lug 84a enters the notch 83a when the w key is depressed, pawl 89 cooperating, in this case, with notch 83e. When the space bar is operated, lever 57 remains inactive and the ratchet 64 is spaced an invariable amount equal to four units of spacing.

Reverse rotation of ratchet 64 is prevented by a pawl 93 (Fig. 3) actuated into engagement with ratchet 64 by a spring 94.

The bearings 60, 61 are adjustably mounted in frame 50. The inner ball race of the front bearing 61 abuts a shoulder formed in shaft 55 and is loosely mounted in a bore in frame 50. This bore is closed by a threaded plug 95 which may be turned to permit moving the bearing and hence shaft 55 longitudinally. The plug 95 is slotted as shown in Fig. 2, and is provided with a screw 96 to lock the plug in its adjusted position.

The rear bearing 60 is similarly mounted on a shoulder on shaft 55 and loose in a bore in the rear portion of frame 50. A threaded bushing 97 is screwed into the rear end of the bore housing bearing 60 and has a slot 97a into which pro-

jects a tongue 98a formed in a ring 98 loose on bushing 97. The ring 98 is notched at regular intervals to enable the ring and hence bushing 97 to be turned with a spanner to adjust the bearing 5 60 longitudinally of the bore. A clip 99 has a tongue engaged in one of the notches in ring 98 to lock the ring and is secured by means of a screw 100 to the frame 50. The screw 100 must be loosened sufficiently to disengage the tongue of clip 99 from the notch in ring 98 before the latter 10 can be turned.

While there has been shown and described and 15 pointed out the fundamental novel features of the invention as applied to a single embodiment it will be understood that various omissions and substitutions and changes in the form and details of the device illustrated and in its operation may be made by those skilled in the art without departing from the spirit of the invention. It is the intention, therefore, to be limited only as indicated by 20 the scope of the following claims.

What is claimed is:

1. In a typewriting machine, typing means, 25 keys for selectively controlling the operation of the typing means, a platen, a carriage on which the platen is mounted, feeding means for the carriage including a ratchet wheel, means controlled by the keys for variably rotating said ratchet according to the widths of characters typed under 30 control of the keys, a device for further controlling the rotation of the ratchet in accordance with the width of a letter previously typed, and means controlled by the keys for setting said device in accordance with the width of each character 35 typed.

2. In a typewriting machine, a platen, a carriage for supporting the platen, typing means cooperating with the platen, keys for selectively controlling the typing means, letter feed mechanism for the carriage, means controlled by said keys for variably controlling the feeding mechanism in accordance with the widths of the characters typed, a device settable in accordance with the width of each character typed and operative 40 to further control the amount the carriage is fed, and means controlled by the keys for setting said device according to the width of the character 45 typed.

3. In a typewriting machine, a carriage, mechanism for typing upon a work sheet, keys for controlling typing mechanism, carriage feed mechanism including a device presettable in accordance with the width of a character typed, said device when set being operative to control the 50 feed of the carriage when the next character is typed, and means controlled by the keys for setting said device as a preliminary to the next typing operation.

4. In a typewriting machine, a carriage and 55 typing means for typing upon a work sheet, carriage feed mechanism, selective means for controlling the typing means, means controlled by the selective means for causing the feed mechanism to advance the carriage an extent dependent upon 60 the width of each character typed, and supplemental means for further controlling the extent of movement of the carriage in accordance with the width of a character typed including a device presettable in accordance with the width of each 65 character typed to condition the feed mechanism for the next typing operation.

5. Feed mechanism for the carriages of typewriting machines comprising a feed ratchet, a pawl for rotating said ratchet, rockable means to support said pawl, means to variably control the 70

movement of the pawl in one direction and presettable means set by movement of the rockable means to control the movement of the pawl in the opposite direction whereby to cause the ratchet to be rotated a variable extent.

6. In combination with the carriage of a typewriting machine, a carriage feed rack, a pinion engaging said rack, a ratchet wheel for rotating said pinion, an arm pivotally mounted adjacent said ratchet, a pawl mounted on said arm and engageable with said ratchet, means to rotate said arm to cause the pawl to rotate the ratchet and hence feed the carriage through said pinion, selective means to limit the forward movement of said pawl, and presettable means controlled by said arm for limiting the return movement of said pawl whereby to govern the extent of movement imparted to the ratchet by said pawl.

7. In feed mechanism for typewriters, a feed ratchet, a feed pawl engageable with said ratchet, means to variably move the pawl in one direction and presettable means controlled by the first-named means for variably selectively controlling the extent of the restoring movement of the pawl.

8. In feed mechanism for typewriter carriages, a carriage feed ratchet, a pawl engageable with said ratchet, means to operate the pawl in a forward direction to rotate the ratchet, selective means to limit the movement of the pawl in a forward direction, additional presettable means for limiting movement of the pawl in the reverse direction including a member settable to a plurality of positions and cooperating with the pawl to control its reverse movement, and means whereby the operating means sets said member according to the extent of forward movement of the pawl.

9. In a typewriting machine, the combination of a carriage for supporting a work sheet, typing means for typing upon the work sheet, means for selectively controlling the operation of the typing means, a carriage feed ratchet, a pawl engaging said ratchet, a rockable arm on which said pawl is mounted, means for operating said arm in a forward direction as an incident to each 40 typing operation, a plurality of devices selectively controlled by the selective means for limiting the forward movement of said pawl in accordance with the width of a character typed, means to restore the pawl, a member settable variable extent for variably arresting the pawl in its restoring movements, and means for setting said member in accordance with the extent of forward movement of the pawl.

10. In a typewriting machine, the combination with a carriage, typing means, selective means for controlling the operation of the typing means, a rotatable member having a connection to the carriage for feeding the carriage, presettable means for controlling the movement of said member in one direction, and means controlled by the selecting means for setting the presettable means in accordance with the width of each character typed including means controlled by the selecting means for limiting the movement of the rotatable member in the other direction in accordance with the width of a character typed.

11. In a typewriting machine, a carriage, typing means, selecting means for controlling the operation of the typing means, a feed rack connected to the carriage, a pinion meshing with said feed rack, a ratchet for rotating said pinion to thereby feed the carriage, a rock arm, a pawl carried by said rock arm and engaging said ratchet, presettable means to limit rotation of the rock 70 75

arm in one direction, selectively settable means for limiting movement of the rock arm in the other direction, and means controlled by the selecting means for operating both the preselecting means and the limiting means.

12. In a typewriting machine, a carriage, typing means, selecting means for controlling the operation of the typing means, a carriage feed ratchet having a driving connection to the carriage to feed the carriage when the ratchet is rotated, a rock arm, a pawl carried by the rock arm and engaging the ratchet whereby when said arm is rocked the ratchet will rotate, a differentially movable lever operative to variably control movement of the rock arm in one direction, means controlled by the selecting means for limiting movement of the rock arm in the opposite direction, said rock arm being operative to set the differentially settable lever in accordance with the extent of movement of the rock arm as limited by the limiting means, and means controlled by the selecting means for operating both the limiting means and the rock arm.

13. In a typewriting machine, a carriage, typing means, selecting means for controlling the operation of the typing means, a rotatable member having connections to feed the carriage when said member is rotated, a variably movable member, means whereby the variably movable member rotates the rotatable member, presetable means to variably limit the movement of said member in one direction, selectively operable means for limiting movement of said member in the opposite direction, said member having means to set the presetable means, and means controlled by the selecting means for operating said member and selectively operable means.

14. In combination with the carriage of a typewriting machine, typing means, selective means for controlling the operation of the typing means, power means for operating the typing means under control of the selective means, means for feeding the carriage variable extents according to the width of each character typed including a member operated as an incident to each typing operation, selectively settable means for governing the operation of said member in one direction, variably settable means for governing the operation of said member in the other direction, and power means controlled by the selective means for operating both variably settable means and the selectively settable means.

15. In combination with the carriage of a typewriting machine, typing means, means to selectively control the operation of the typing means, a carriage feed rack, a pinion engaging said rack, a ratchet for rotating said pinion, a lever mounted coaxially with said ratchet, a pawl on said lever engageable with said ratchet, a plurality of cams selectively operable to limit movement of said lever in one direction to rotate said ratchet, a second lever having a series of stop portions on different levels, means on the first lever to cooperate with the stop portions on the second lever to limit movement of the first lever in the opposite direction, said second lever being differentially settable by said first lever in accordance with the extent of movement of said first lever as determined by said cams, and means controlled by the selective means for selectively operating both the cams and the first lever.

16. In combination with a carriage for a typewriting machine, typing means, selective means for controlling the operation of the typing means, a carriage feed ratchet, means to connect said

ratchet to the carriage whereby the rotation of the ratchet feeds the carriage, a rock lever mounted adjacent said ratchet a pawl on said rock lever engaging said ratchet, selectively operable cam means for limiting the rotation of said rock lever in one direction, a stop lever movably mounted so as to be selectively settable to any one of a plurality of positions and provided with stop portions cooperating with said rock lever to variably limit its movement in the opposite direction, said rock lever having means to position the stop lever in accordance with the movement of said rock lever as delimited by the cam means, and power means controlled by said selective means for operating the lever and selectively operating the cam means.

17. In combination with the carriage of a typewriting machine, typing means, keys for controlling the typing means, a plurality of selecting bails cooperating with said keys, means whereby each key operates one of said bails; means to feed the carriage variable extents according to the key operated comprising a carriage feed ratchet, a movable member, a pawl on said member cooperating with the ratchet to rotate same, a stop lever variably settable by said movable member for determining the extent of movement of said member in one direction, and selectively operable cam means for determining the extent of movement of said member in the opposite direction; and power means controlled by said bails for selectively operating the cam means and operating said movable member.

18. In a typewriting machine, a carriage, typing means, power means for operating the typing means, keys for controlling the operation of the typing means by the power means, a series of control members selectively operated by the keys; means for feeding the carriage including a feed pinion and a rack meshing therewith, ratchet and pawl means for rotating said pinion to feed the carriage, presetable means for limiting the movement of the ratchet and pawl means in one direction, selectively settable means for limiting the movement of said pawl in the opposite direction, means whereby the ratchet and pawl means variably sets the presetable means in accordance with the extent of movement of the ratchet and pawl means permitted by the limiting means, and power means controlled by said control members for operating the ratchet and pawl means and selectively controlling the limiting means.

19. In a variable feed mechanism for the carriages of typewriting machines, a rotatable element operatively connected with the carriage whereby rotation of the element feeds the carriage, means rotatably mounted adjacent the rotatable element and having means to couple the rotatable means and rotatable element together whereby movement of the rotatable element, means to variably selectively determine the extent of rotation of the rotatable element by said means, means to restore the rotatable element to its initial position, variably settable means for determining the extent of restoring movement of the rotatable means, and means operated by the rotatable means in accordance with its extent of rotation for positioning the variably settable means whereby to predetermine the extent of feed imparted to the carriage upon a subsequent operation of the feeding mechanism.

20. In combination with the carriage of a typewriting machine, typing means, means to selec-

tively control the operation of the typing means; a carriage feed ratchet, a lever mounted coaxially with said ratchet, a pawl on said lever engageable with said ratchet, a plurality of cams selectively rotatable to determine the extent of movement of said lever in one direction to rotate said ratchet, a second lever, one of said levers having a series of stop portions on different levels, means on the other lever to cooperate with any one of the stop portions to limit movement of the first lever in the opposite direction, said second lever being differentially settable by said first lever to render one of the stop portions effective in accordance with the extent of movement of said first lever as determined by said cams, and means controlled by the selective means for selectively rotating the cams.

21. In a typewriting machine, typing means, keys for selectively controlling the operation of the typing means, a platen, a carriage on which the platen is mounted, feeding means for the carriage including a rotatable element, means controlled by the keys for variably rotating said element according to the widths of characters typed under control of the keys, a device for further controlling the rotation of said element in accordance with the width of a letter previously typed, and means controlled by the keys for variably selectively setting said device in accordance with the width of each character typed.

22. In a typewriting machine, a platen, a carriage for supporting the platen, typing means cooperating with the platen, means for selectively controlling the typing means, letter feed mechanism for the carriage, means controlled by said selective controlling means for variably controlling the feeding mechanism in accordance with the widths of the characters typed, a device settable in accordance with the width of each character typed and operative to further control the amount the carriage is fed, and means controlled by the selective controlling means for setting said device according to the width of the character typed.

45 23. In a typewriting machine, a carriage, mechanism for typing upon a work sheet, means for selectively controlling typing mechanism, carriage feed mechanism including a device pre-settable in accordance with the width of a character typed, said device when set being operative to control the feed of the carriage when the next character is typed, and means controlled by the first named means for setting said device as a preliminary to the next typing operation.

55 24. In a typewriting machine, a carriage and typing means for typing upon a work sheet, carriage feed mechanism, keys for controlling the typing means, means controlled by the keys for causing the feed mechanism to advance the carriage an extent proportional to the width of each character typed, and supplemental means for further controlling the extent of movement of the carriage in accordance with the width of a character typed, including a device presettable 65 in proportion to the width of each character typed to condition the feed mechanism for the next typing operation.

25. Feed mechanism for the carriages of typewriting machines comprising a rotatable element, 70 means for rotating said element, means to variably rotate said element in one direction and presettable means controlled by the rotating means to control the movement of said element in the opposite direction whereby to cause the 75 rotatable element to be rotated a variable extent.

26. In combination with the carriage of a typewriting machine, a carriage feed ratchet, an arm pivotally mounted adjacent said ratchet, a pawl mounted on said arm and engageable with said ratchet, means to rotate said arm to cause the pawl to actuate the ratchet and hence feed the carriage, selective means to limit the forward movement of said pawl, and presettable means actuated by said arm for limiting the return movement of said pawl whereby to govern 10 the extent of movement imparted to the ratchet by said pawl.

27. In feed mechanism for typewriter carriages, a carriage feed ratchet, a pawl engageable with said ratchet, means to operate the pawl in a 15 forward direction to actuate the ratchet, means to restore the pawl, selective means to limit the restoring movement of the pawl, including a stop member selectively settable to a plurality of positions and cooperating with the pawl to 20 control its reverse movement, and means whereby the operating means selectively sets said member according to the extent of forward movement of the pawl.

28. In a typewriting machine, the combination 25 of a carriage for supporting a work sheet, typing means for typing upon the work sheet, means for selectively controlling the operation of the typing means, a carriage feed ratchet, a pawl engaging said ratchet, a movable member on 30 which said pawl is mounted, means for operating said movable member in a forward direction as an incident to each typing operation, a plurality of devices selectively controlled by the selective means for limiting the forward movement of said movable member in accordance with the width of a character typed, means to restore the movable member, a stop member settable variable extents for variably arresting the movable member in its restoring movements, 40 and means for setting said stop member in accordance with the extent of forward movement of the movable member.

29. In a typewriting machine, the combination with a carriage, typing means, selective means 45 for controlling the operation of the typing means, a rotatable member having a connection to the carriage for feeding the carriage, presettable stop means for controlling the movement of said member in one direction, and means controlled 50 by the selecting means for setting the presettable means in accordance with the width of each character typed including selective stop means, means controlled by the selecting means for limiting the movement of the rotatable member in 55 the other direction in accordance with the width of a character typed.

30. In a typewriting machine, a carriage, typing means, selecting means for controlling the operation of the typing means, a feed rack connected to the carriage, a pinion meshing with said feed rack, a ratchet for rotating said pinion to thereby feed the carriage, a rock arm, a pawl carried by said rock arm and engaging said ratchet, a differentially settable stop member for limiting rotation of the rock arm in one direction, selectively settable means for limiting movement of the rock arm in the other direction, and means controlled by the selecting means for setting both the preselecting means and the limiting means. 70

31. In a typewriting machine, a carriage, typing means, selecting means for controlling the operation of the typing means, a carriage feed ratchet having a driving connection to the carriage to feed the carriage when the ratchet is 75

rotated, a rock arm, a pawl carried by the rock arm and engaging the ratchet whereby when said arm is rocked the ratchet will be actuated, a differentially movable stop lever operative to 5 variably control movement of the rock arm in one direction, means controlled by the selecting means for limiting movement of the rock arm in the opposite direction including a second differentially settable lever, said rock arm being 10 operative to set the second differentially settable lever in accordance with the extent of movement of the rock arm as limited by the limiting means, and means controlled by the selecting means for operating both the limiting means and 15 the rock arm.

32. In a typewriting machine, a carriage, typing means, selecting means for controlling the operation of the typing means, a rotatable member having connections to feed the carriage when 20 said member is rotated, a variably movable member, coupling means whereby the variably movable member rotates the rotatable member in one direction only, differentially presettable stop means to variably limit the movement of said

member in one direction, selectively operable stop means for limiting movement of said member in the opposite direction, said member having means to differentially set the presettable means, and means controlled by the selecting means 5 for operating said member and selectively operable means.

33. In combination with the carriage of a typewriting machine, typing means, selective means for controlling the operation of the typing means, 10 power means for operating the typing means under control of the selective means, means for feeding the carriage variable extents according to the width of each character typed including a variably movable member operated as an in- 15 cident to each typing operation, selectively settable means for variably controlling the movement of said member in one direction, differentially settable means for governing the movement of said member in the other direction, and 20 power means controlled by the selective means for operating both the differentially settable means and the selectively settable means.

RONALD D. DODGE.
